UNITED STATES PATENT OFFICE.

LOUIS S. MORRIS, OF BRIDGEPORT, CONNECTICUT.

INTERNAL-COMBUSTION ENGINE.

1,249,806.

Specification of Letters Patent. Patented Dec. 11, 1917.

Application filed March 31, 1914. Serial No. 828,536.

To all whom it may concern:

Be it known that I, LOUIS S. MORRIS, a citizen of the United States, residing at Bridgeport, in the county of Fairfield and State of Connecticut, have invented a new and useful Internal-Combustion Engine, of which the following is a specification.

My invention relates to internal combustion engines of the rotary or turbine type where there is provided a rotor carrying sliding pistons, which, acting in conjunction with the stator, will suck the explosive mixture into the engine, compress it to the extent desired, and, on the explosion of the compressed mixture, the rotor will be operated to scavenge the chamber and suck in and compress new charges.

My object is to produce an internal combustion engine of the rotary or turbine type which will be simple in construction, highly efficient in service and of great power relatively to the fuel consumption.

These and further objects will appear from the following specification and accompanying drawings taken together or separately.

My invention is illustrated in the drawings in which the same parts are designated by similar reference characters in all the figures.

Figure 1 represents a half longitudinal section and half side elevation of my improved engine showing the parts in position immediately prior to the explosion, and suction periods, and nearing the ends of the compressing and scavenging periods.

Fig. 2 is a similar view showing the parts in position for firing, suction, compressing and scavenging.

Fig. 3 is a sectional view on the line 3—3 of Fig. 1.

Fig. 4 is a sectional view on the line 4—4 of Fig. 1.

Fig. 5 is an elevation of a portion of a cheek plate, and

Fig. 6 is a side elevation partly in section of a modification.

A stationary casing or stator 1 is provided and this casing may be firmly secured to a suitable floor or foundation (not shown), and the casing is provided with suitable bearings 2—2 which support the shaft 3. These bearings are carried in side plates 4. The side plates, at their peripheries are rigidly secured to an annulus 5. The annulus and the side plates together form the stator

of the engine. The annulus and the side plates are suitably water jacketed to prevent excessive heat, as is well known.

The bore of the annulus is not cylindrical in its entirety but is formed of a series of semi-lunes *a*, *b*, *c* and *d*, with short cylindrical spaces 6 between them.

The annulus is provided with two inlet ports 7, 7 and two outlet ports 8, 8. Adjacent to each inlet port 7 is a spring actuated, air cushioned valve 9. These valves, as shown in Figs. 1 and 2, are diametrically opposite each other. While I have shown the inlet valves in Figs. 1 and 2, it is obvious that they may be omitted as shown in Figs. 6 without affecting the operativeness of the device.

In the embodiment illustrated I show a pair of oppositely disposed transfer valves 10, 10 and these valves are shown as 90° from the inlet valves.

Carried on the shaft 3 is a rotor 11 which, in the embodiment illustrated, will serve as a fly wheel, and carried by the rotor is a plurality of piston slides, *e*, *f*, *g*, *h*, *i*, *j*, *k*, and *l* evenly spaced around said rotor.

On the inner face of each side plate 4 is a recess 12 and in each recess is seated a cheek ring 13. These cheek rings bear against the sides of the rotor at its peripheral edge and are made of hardened material to prevent wear at this point.

The rotor 11 is provided with a plurality of radial slots 14 which extend inward from the periphery and each communicates with a pocket 15. These slots and pockets extend from side to side of the rotor 11. In each slot is carried a piston slide and each slide is provided at its inner end with a shoulder 16, and between each shoulder and a wear plate 17 at the base of each pocket 15 is a spring 18 tending to force the piston slide outward. The outer face of each piston slide is provided with a semi-cylindrical groove into which is fitted a correspondingly shaped wear block 19. The outer face of the block 19 is of the same curvature as the bore of the annulus 5. Carried in each slot 14 and forming wearing surfaces for the slide piston therein is a pair of tapered plates 20 of case hardened metal. Each plate is held in place by a key 21 and the key way in the plate is made larger than its key so that when the piston is moved outward it will carry the plates with it more or less and binding will be prevented. When

the pistons are in their outermost positions the gas is not under pressure and there will be no tendency for gas to leak past the plates 20 during compression for the reason that as 5 the piston is immediately started inward and carries the plates with it, thus making a tight joint between the plates and the sides of the slot, and the plates and the piston. As soon as the explosion occurs the piston 10 starts to move inward. When the piston is returned the plate will be brought back with it and on account of its edge shape, will closely grasp the piston and prevent leakage at this point.

15 In each cylindrical part 6 of the bore of the annulus is inserted a hardened wear strip 22 to prevent leakage at this point.

The inlet valves 9 are identical and a description of one will suffice for both. The 20 valves extend the entire width of the rotor and are carried in housings 23, 23 formed integrally with the annulus 5. The valve comprises a block having a passage 24 which communicates with the inlet port 7 on one 25 side and with a lune shaped compression space on the other side when the valve is in its innermost position. The outer side of the block is provided with a cylindrical extension 25 and surrounding this extension 30 and interposed between the block and the cap of the housing is a spring 26 which tends to normally seat the block in engagement with the periphery of the rotor. In the cylindrical extension 25 is a piston 27 carried on an 35 adjusting screw 28 and the wall of the extension is provided with a series of perforations for admitting air or other fluid to the cylinder below the piston.

The transfer valves are identical in every 40 respect with the inlet valves except that in addition to the openings for the passage of the gas, the block contains a cavity 29 for holding a charge of compressed gas.

The annulus is provided with lugs 30 and 45 the side plates have similar shaped lugs 31 and bolts 32 are passed through these lugs to hold the whole structure securely together.

The operation of my improved engine is as follows:

50 With the parts in the position shown in Fig. 1 the rotor will be turned in a clockwise direction by any approved means and as the piston slide *e* passes from under the inlet valve 9 the valve will be forced inward by its spring and communication between the inlet port 7 and the space *a* will be opened through the passage 24. The piston *e*, having been forced outward by the spring 18, will now begin to suck gas 55 through the port. As the piston *e* approaches the end of the space *a* it will be forced inward by the wall of the space, and the piston *l* will come under the valve 9 and raise it cutting off the supply of gas. The 60 gas drawn in by the piston *e* will be con-

fined in the space between the pistons *e* and *l* and as the piston *l* approaches the end of the space *a* the gas will be compressed and forced into the cavity of the transfer valve 10 which has been raised by the piston *e* 70 until its inlet passage comes into coincidence with a similar opening 33 in the housing. The movement of the rotor will carry the piston *e* from beneath the transfer valve 10 which will descend and the charge of 75 compressed gas will rush out of the cavity 29 behind the piston *e* and be exploded by the sparking device 34. This explosion will drive the piston *e* in the clockwise direction until it passes the exhaust 8. The piston 80 slide *l* will in the meantime have passed the transfer valve 10 and be driven around by the new explosion and will scavenge the space *b* of the products of combustion of the first explosion. This operation will be repeated 85 on each side of the engine or as many times as there are transfer valves and spark plugs and as many times as there are piston slides.

When the inlet and transfer valves are raised by the piston slides the perforations 90 in the extensions 25 will be masked by the pistons 27 and the air imprisoned below the pistons will act as a cushion and its expansive force will aid the spring 26 in seating the valve.

95 The springs 18 need be of a strength only sufficient to move the slide pistons radially outward during the cranking operation. When the engine begins to turn over owing to the explosions of the gas, the centrifugal 100 force will be sufficient to operate the piston slides without the aid of the springs.

The blocks 19 may be provided with serrations 35, as shown in order to minimize leakage past them and to form oil spaces between them to lubricate the interior of the 105 engine.

When the form of the apparatus shown in Fig. 6 is used, outer walls of the spaces *a*, *b*, *c* and *d* are made on parabolic curves with 110 the surface *a*¹ leading up gradually from a point near the gas checks 22. This surface *a*¹ will allow the piston slides to move out gradually and prevent slamming or pounding.

115 Instead of the reciprocating inlet and transfer valves shown, I may use valves of the rotating or oscillating type operated in phase with the rotor, and driven from the shaft 3 or other movable part. Such rotary 120 valves, when used, will be positively acting, and no springs or cushions will be required.

In accordance with the provisions of the patent statute I have described the principles of my invention together with the apparatus which I now consider to represent the best embodiment thereof, but I desire to have it understood that the apparatus is merely illustrative and that the invention may be carried out in other ways.

Having now described my invention, what I claim and desire to secure by Letters Patent of the United States is:

1. An internal combustion engine comprising a stator, a fuel inlet in the stator, an inlet valve, a tapering fuel chamber in the stator, a rotor mounted in the stator, a piston slide movable radially in the rotor, tapered, adjustable plates carrying the piston slide, cheek plates between the rotor and the stator and gas checks carried by the stator.
2. An internal combustion engine, comprising a stator and a rotor, a tapering compression chamber in the stator, a transfer valve, a piston slide movable radially in the rotor and engaging the walls of the compression chamber, whereby gas will be compressed in the chamber, there being a pas-

sage at the small end of the compression chamber, means whereby the piston slide may engage the transfer valve and move it into position to receive the compressed charge from the compression chamber, a combustion chamber, positively acting means for moving the transfer valve into position behind the piston slide when the latter has been moved from engagement with the valve whereby the compressed charge in the valve will be behind the piston slide and in the combustion chamber, and means for igniting the charge.

This specification signed and witnessed this 23rd day of March, 1914.

LOUIS S. MORRIS.
